UNITED STATES PATENT OFFICE.

DANIEL W. TOWER, OF GRAND RAPIDS, MICHIGAN, ASSIGNOR TO THE
GRAND RAPIDS BRASS CO., OF GRAND RAPIDS, MICHIGAN.

DESIGN FOR A KNOB.

SPECIFICATION forming part of Design No. 35,239, dated October 29, 1901.

Application filed September 30, 1901. Serial No. 77,160. Term of patent 3½ years.

To all whom it may concern:

Be it known that I, DANIEL W. TOWER, a citizen of the United States, residing at Grand Rapids, in the county of Kent and State of Michigan, have invented and produced a new and original Design for a Knob, of which the following is a specification.

This invention relates to a new and original design for a knob, and the essential features reside in the knob as illustrated in the accompanying drawings, wherein—

Figure 1 is a front elevation of the knob embodying the features of the design. Fig. 2 is a side elevation of the same. Fig. 3 is a transverse vertical section on the line 3—3, Fig. 2, looking in the direction of the arrows.

The design is characterized by a body 1, having an outer enlargement and a rear con-

tracted neck, the body and neck being traversed by curved corrugations 2. On the rear terminal of the neck is a polygonal base 3, having a number of facets 4, extending to a rear circumferential rim 5, and from the center of the base a projection 6 extends rearwardly.

Having thus described the invention, what is claimed as new is—

The design for a knob, as herein shown and described.

In testimony that I claim the foregoing as my own I have hereto affixed my signature in the presence of two witnesses.

DANIEL W. TOWER.

Witnesses:

GEORGE F. SINCLAIR,
H. EMORY PEASE.
